Attorney.

UNITED STATES PATENT OFFICE.

ALFRED JONSSON, OF LIDKÖPING, SWEDEN.

DRILL-CHUCK.

1,249,766.

Specification of Letters Patent. Patented Dec. 11, 1917.

Application filed September 7, 1917. Serial No. 190,132.

To all whom it may concern:

Be it known that I, ALFRED JONSSON, a subject of the King of Sweden, and resident of 329 Norra Kyrkogatan, Lidköping, in the 5 Kingdom of Sweden, have invented certain new and useful Improvements in Drill-Chucks, of which the following is a specification.

The present invention refers to drill 10 chucks of the kind where a number of rotary tumblers are in gear with an exterior shell acted upon by a spring and which, when the shell is rotated against the action of the spring, are turned in such a manner that 15 their edges, which hold the drill, are removed from each other, so that drills of different size and cross section can be inserted between the same. When the shell is then released, it is turned back under the 20 action of the spring, so that the tumblers are applied against the drill and securely hold the same.

The characteristic feature of the present 25 invention consists in this that the teeth extend over the whole or nearly whole length of the tumblers and gear with corresponding teeth on the inside of the shell, and that the tumblers are rotary and detachably located on pivots that are firmly secured 30 within the body of the chuck. By this combination several important advantages are attained.

Hereby it will first and foremost be possible to change the chuck from right working 35 to left working, so that one and the same chuck can be used for right cutting as well as for left cutting drills. For this changing of the chuck it is only required to take out and turn over the tumblers as well as the 40 spring acting upon the shell.

Another advantage is that the pressure from the drill is wholly taken up by the said pivots and is, thus, prevented from being transmitted to the shell.

45 A practical form of construction is illustrated on the accompanying drawing. Figure 1 shows the chuck in side elevation and partially in section. Fig. 2 is an end view with the cover removed. Fig. 3 shows a 50 similar view with the tumblers in another position. Figs. 4 and 5 show a tumbler in side view and end view respectively.

The tumblers 1, which are rotary and detachably mounted on pivots 2 firmly secured within the chuck, are provided with 55 teeth 3 extending over the whole length of

the same and gear with corresponding teeth 4 on the inside of the shell 5. A spring 6 operates to normally hold the tumblers in operative position in which they securely hold the drill (position shown in Fig. 2). On the lower side there is a cover 7 provided with a central hole 9 for the drill. The cover is secured by means of screws 8 which are screwed into holes provided in 65 the pivots 2.

By rotating the shell, which is roughened on its outer side, in the direction of the arrow (Fig. 3) the tumblers are turned so as to be removed from each other, whereby 70 the drill is released. By this means it will be possible to remove a drill during the working of the machine and insert another.

Due to the fact that the teeth 3 extend over the whole or nearly the whole length 75 of the tumblers and gear with corresponding teeth 4 on the inside of the shell, and due to the tumblers being located on the fixed pivots 2, the application of the tumblers against the drill will be just as efficacious in any position they may occupy and a sliding of the drill can, thus, not take place, and nor is the shell exposed to any pressure which can render difficult the rotation of the same. 85

Moreover, the considerable advantage is attained, as has been indicated above, that the chuck can be employed for both right and left cutting drills. If it be assumed that the drill is on the drawing adjusted for 90 right cutting drills (*i. e.* drills cutting when rotating clockwise) and if it is desired to change the chuck and have it adapted for left cutting drills, one has only to remove the cover 7 by unscrewing the screws 8 and 95 draw off the tumblers from the pivots 2 secured in the bottom 10, turn them over and pass them on to the pivots again, so that the end having previously been turned downward will come upward. Moreover, the 100 spring 6, whose ends are bent and maintained in notches provided in the shell and in the bottom 10 respectively, is also turned over.

Having now described my invention, what 105 I claim as new and desire to secure by Letters Patent is:

1. A drill chuck comprising a main rotary member, a plurality of pivot pins fixed thereon, a spring-actuated shell surrounding said main rotary member, a tumbler rotatably mounted on each of said pins and 110

2
having a sector of teeth on one side thereof, teeth on the inside of said spring-actuated shell engaging with the teeth on the tumblers, an eccentric gripping surface on each of said tumblers arranged at the same level as the teeth thereon with respect to a plane at right angles to the pivot pins, and a removable cap member for holding said tumblers in position.

- 5 10 2. A drill chuck comprising a main rotary member, a plurality of pivot pins fixed thereon, a spring-actuated shell surrounding said main rotary member, a tumbler rotatably mounted on each of said pins and having a sector of teeth extending throughout the whole length of the tumbler, teeth on the inside of said spring-actuated shell engaging with the teeth on the tumblers, an eccentric gripping surface on each of said 15 tumblers also extending throughout the whole length of the tumbler, and a removable cap member for holding said tumblers in position.
- 15 20 25 3. A drill chuck comprising a main rotary member, a plurality of pivot pins fixed thereon, a shell surrounding said main rotary member, a spring tending to rotate said shell around said member and reversible so as to actuate said shell in either direction, a tumbler rotatably mounted on each of said pins and having a sector of teeth extending throughout the whole length of the tumbler, teeth on the inside of said shell engaging with the teeth on the tumblers, an eccentric, serrated, gripping surface on each of said tumblers also extending throughout the whole length of the tumbler, a removable cap member for holding said tumblers in position, and screws for attaching said cap member to the pivot pins.
- 30

35 pins and having a sector of teeth on one side thereof, teeth on the inside of said spring-actuated shell engaging with the teeth on the tumblers, an eccentric gripping surface on each of said tumblers arranged at the same level as the teeth thereon with respect to a plane at right angles to the pivot pins, and a removable cap member for holding said tumblers in position.

40 4. A drill chuck comprising a main rotary member, a plurality of pivot pins fixed thereon, a shell surrounding said main rotary member, a spring tending to rotate said shell around said member and reversible so as to actuate said shell in either direction, a tumbler rotatably mounted on each of said pins and having a sector of teeth extending throughout the whole length of the tumbler, teeth on the inside of said shell engaging with the teeth on the tumblers, an eccentric, serrated, gripping surface on each of said tumblers also extending throughout the whole length of the tumbler, a removable cap member for holding said tumblers in position, and screws for attaching said cap member to the pivot pins.

45 In witness whereof I have hereunto set my hand.

ALFRED JONSSON.
